UNITED STATES PATENT OFFICE.

SAMPSON D. FOSTER, OF SAN DIEGO, CALIFORNIA.

PERMUTATION-LOCK.

1,316,946.

Specification of Letters Patent. Patented Sept. 23, 1919.

Application filed June 1, 1916. Serial No. 101,162.

To all whom it may concern:

Be it known that I, SAMPSON D. FOSTER, a citizen of the United States, residing at San Diego, in the county of San Diego and State 5 of California, have invented certain new and useful Improvements in Permutation-Locks, of which the following is a specification.

My invention relates broadly to locks and more particularly has reference to a motor 10 vehicle steering post lock.

As the primary object, it is contemplated by this invention to provide a device of the above character for locking the front wheels of a vehicle in a rigid position so as to prevent a theft of the vehicle on which the 15 device is mounted.

More particularly this invention contemplates the provision of a slideable bolt which forms a part of a permutation locking 20 means, the bolt being adapted to engage openings in both the steering post and the casing thereof, removal of the bolt being effected by working the combination and withdrawing the bolt.

It is a more specific object of this invention to provide means for locking the lock 25 casing to the base plate; to provide common means for facilitating the proper positioning of the locking means and maintain the bolt in proper position after it has been removed from the post; to provide resilient 30 means for causing the bolt to automatically engage the steering post after being released.

A still further object of my invention 35 resides in the provision of a device of the character described that is simple in construction, efficient in operation and one that can be manufactured and placed on the market at a minimum cost.

Other objects as well as the nature, characteristic features and scope of my invention 40 will be more readily understood from the following description taken in connection with the accompanying drawings and pointed out in the claims forming a part of this specification.

One practical form of construction and assembly will be described and illustrated in the accompanying drawings, in which:—

Figure 1 is a side elevation of my invention in position,

Fig. 2 is a longitudinal section taken on the line 2—2 of Fig. 1, the post and casing therefor being shown in transverse section,

Fig. 3 is a transverse section taken on the

line 3—3 in the direction in which the arrow points,

Fig. 4 is a transverse section taken on the line 4—4 of Fig. 2 in the direction in which the arrow points,

Fig. 5 is a transverse section taken on the line 5—5 of Fig. 2 in the direction in which the arrow points, and

Fig. 6 is a transverse section taken on the line 6—6 of Fig. 2.

Referring more particularly to the drawings in which similar reference numerals designate like and corresponding parts through the different views, I have illustrated the dash board 1 of a motor vehicle 70 through which is rotatably mounted the usual steering post 2, while a tubular casing 3 surrounds the post 2. Disposed about the casing 3 and rigidly connected to the dash board is the base 4 of my improved 75 lock. The base 4 is provided with a threaded recess 5 in the bottom of which there is provided an opening that is arranged in alignment with the opening in the casing 3. In these alining openings there is mounted an ex- 80 teriorly threaded sleeve 6 the bore of which is adapted to align with an opening 7 in the post 2 for a purpose to be hereinafter described.

Adapted to be associated with the recess 5 is a tubular casing 8 that is provided with screw threads at each end. A screw cap 9 is attached to the outer end of the casing 8 and is held thereon through the medium of a locking screw 10. This cap is provided on 90 its outer surface with a central recess 11, and the bottom of this recess is provided with a central opening 12 that communicates with the interior of the casing.

The improved locking means is arranged 95 in the casing 8 preparatory to the application of the casing to the base and in the present instance consists of an elongated bolt 13. One end of the bolt passes through the opening 12 and has secured 100 thereon a knob 14. The knob is retained in position by means of a lock screw 15 as shown in Fig. 2. A plurality of lugs 16, 17, 18, 19 and 20 extend laterally from the bolt in uniformly spaced relation and in different 105 directions. The lugs 19 and 20 may be in the form of a transverse pin that passes through the bolt, and the lugs project from the bolt 13 and the lug 19 is longer than the lug 20 as shown in Fig. 6. A coil spring 21 110

is arranged about the bolt with its ends bearing against the cap and a small washer 22 arranged adjacent the lugs 19 and 20. It will be noted that the two lugs 19 and 20 hold the washer horizontal. A sleeve 23 is now arranged within the casing and its diameter is slightly less than the diameter of the casing. A flange 24 projects from the inner periphery of the sleeve and is provided with a slot 25 and a recess 26 on the inner surface. A disk 27 is now applied about the bolt until it engages the sleeve 23, application over the lugs being effected through the medium of a slot 28 which extends from the edge to the central opening therein. A pin 29 depends from this disk and is arranged so as to be engaged by the lug 19. Another sleeve 30 of a diameter similar to the sleeve 23 is inserted in the casing and following this another disk 31 similar in construction to the disk 27 is applied. However, two pins 32 depend from one lateral face of the disk 31, and are placed upon the opposite sides of the slot so that they may be engaged by the lug 18. This disk 31 has near its periphery a pin 33 that projects from the other lateral face and is placed about 90° distant from the pins 32. Another sleeve 34 is now inserted in the casing and is similar in construction to the sleeve 30. Still another disk 35 is placed in the casing and this disk is similar in construction to the disk 31 and although it has spaced depending pins 36, it is not provided with an upright pin. Finally another sleeve 37 is arranged in the casing and has the outer edge associated in alinement with the edge of the casing. The casing, having the respective ends screw threaded, is arranged so that the locking bolt may be passed through the sleeve 6 to permit of the engagement of the threaded end with the recess 5 whereupon by tightening the casing the inner edge of the casing and the inner edge of the end sleeve 37 are brought to bear against the bottom of the recess 5 in the body 4, the parts being maintained in this position through the medium of a locking screw 38.

50 The operation of my invention is as follows:—

To facilitate the operation of the device I have provided the knob 14 with a plurality of graduations 39, preferably three inches 55 divided into eighths and numbered 0—1—2 at each inch mark. The cap 9 is provided with an indicator 40. Assuming that the device is arranged in a locked position as illustrated in Fig. 2, and it is desired to remove the free end of the bolt 13 from engagement with the post 2, the bolt is rotated twice to the right until the one and three eighths inch mark registers with the indicating line 40. During this movement the 60 lug 19 engages the pin 29; the lug 18 en-

gages one of the pins 32; and the pin 33 engages one of the pins 36, which movement places the slot in the disk 35 in position to aline with the lug 16 when all the lugs and slots have been suitably adjusted. The bolt 13 is now rotated to the left or in an opposite direction until the one and one eighth inch mark registers with the line 40 and during this movement the lug 19 will engage the pin 29 and the lug 18 will engage 75 one of the pins 32, which movement consequently places the disk 31 for alinement with the lug 17. The bolt 13 is again rotated to the right until the two and one eighth mark registers with the indicating indicator 40 so that the lug 19 will engage the pin 29 so as to place the disk 27 in alinement with the lug 18. Finally the bolt is rotated to the left until 0, alines with the indicator 40 which places the lug 19 in alinement with the slot 25 in the flange, and as all of the lugs are now in alinement with the adjacent disks by pulling the bolt outwardly and turning it a slight extent, the lug 19 will become engaged in the recess 26 and in this manner hold the bolt in unlocked position. In order to lock the bolt it is necessary to revolve the bolt once to the right in order that the lug 19 will be placed in alinement with the slot 25 in the flange, which movement also places the lugs 16, 17 and 18 in alinement with the slots in the disks 27, 31 and 35, respectively, the disks 31 and 35 having the spaced pins 32 and 36 respectively which act as guides for the lugs 16 100 and 17.

One of the most important features of this invention is the arrangement of the upright pin 33 on the disk 31 which is positioned adjacent the outer edge of said disk 105 so that it will engage the pins 36 when it is rotated but will not be engaged by the short lug 17.

It is to be appreciated that I am not to be limited to the specific arrangement of 110 disks, pins, and lugs nor the particular combination described, since it is apparent that by slightly altering the positions of the pins and lugs various combinations will be provided but this form is preferred over other 115 arrangements.

Because I have described the preferred form of my invention it will be understood that I am not to be limited thereto, however, I desire that great stress be laid upon 120 the arrangement of the combination and permutation locking means coöperating with the main locking bolt, the bolt being adapted for removable engagement with the steering rod for preventing actuation thereof for the 125 purpose set forth.

Having thus fully described my invention, what I claim as new and desire to secure by Letters Patent, is:—

1. A permutation lock, comprising a base, a 130

tubular casing secured to the base, a plurality of disks mounted in the casing and each provided with a slot, a cap secured to the outer end of the casing, said cap provided in the outer face with a recess, a rotatable and slideable bolt extending through the cap and disks, lugs on the bolt for engaging the disks and adapted to pass through the slot in the disks, and a knob secured to the outer end of the bolt and adapted to normally be received in the recess in the cap.

2. A permutation lock, comprising a base, a tubular casing secured to the base, a plurality of disks mounted in the casing and each provided with a slot, sleeves arranged in the casing for spacing the disks, a cap secured to the outer end of the casing, said cap provided in the outer face with a recess, a rotatable and slideable bolt extending through the cap and disks, lugs on the bolt for engaging the disks and adapted to pass through the slots in the disks, a knob secured to the outer end of the bolt, and a spring for normally holding the knob in the recess of the cap.

3. A permutation lock including a base member, a lock casing mounted on the base member, a locking bolt rotatably and slid-

ably mounted in the lock casing, a plurality of lugs extending laterally from the bolt and arranged in uniformly spaced relation thereon, a plurality of disks, a plurality of sleeves mounted in the casing and arranged alternately with the disks so as to suitably mount the disks in spaced relation, each of the disks being provided with slots to permit of the passage of lugs therethrough, pins depending from the disks and arranged adjacent the slots, an upright pin on one of the disks for coöperating with the depending pins on the adjacent disk, a knob carried by the bolt and positioned exteriorly of the casing and provided with a plurality of graduations, and a casing provided with an indicating mark for coöperating with the graduations on the head so that by rotating the head in various directions the pins and lugs will coöperate with each other so as to arrange the lugs in alinement with the slots to permit of the bolt being withdrawn from locking position.

In testimony whereof I affix my signature in presence of two witnesses.
